CAR TRUCK

James A. Shafer, East Cleveland, Ohio, assignor to
 National Malleable and Steel Castings Company, Cleveland, Ohio, a corporation of Ohio

Application June 7, 1943, Serial No. 489,874

6 Claims. (Cl. 105—197)

The present invention is a modification of the type of truck described and claimed in Shafer Patent No. 2,187,434, January 16, 1940, in which the bolster supporting springs are arranged on two levels, the upper springs being housed within the bolster end and directly supporting the bolster, and the lower springs being housed within the side frame and supporting the bolster through downwardly extending trunnions formed integrally with said bolster. In this type of truck, friction means are interposed between the lower springs and the trunnions.

The present invention relates to trucks of increased spring capacity capable of carrying heavier loads than the types of truck shown in the above-mentioned patent.

In the drawings:

Figure 1 is an elevational view of a car truck embodying my invention, one half of which is shown in vertical section.

Figure 2 is a horizontal sectional view, taken on line 2—2 of Figure 1.

Figure 3 is a vertical sectional view, taken on line 3—3 of Figure 1.

Figure 4 is an oblique view of the means for supporting one of the springs and for locking down certain of the frictional parts.

Referring to the drawings, the side frame 10 is formed with a tension member 11, compression member 12 and connecting columns 13, 13. The central portion 14 of tension member 11 is of box section having a bottom wall 15, side walls 16, 16 and a top wall or shelf 17. Shelf 17 is formed with openings 18, 18 receiving the friction mechanism.

In the present invention two springs 19, 19 (preferably double coil springs) are housed within the tension member 11, seating upon the bottom wall 15 thereof, and three springs 20, 20, 20 are housed within the end of bolster 21, thus providing a spring group consisting of five springs. The three upper springs 20 are arranged side by side lengthwise of the bolster 21, the axis of the center one of these springs coinciding with the intersection of the center lines of bolster and side frame. These three springs 20 bear at their upper ends against the top wall 22 of the bolster 21 and extend down through the open bottom portion of the bolster.

On each side of the center one of these springs is a trunnion 23 integral with the bolster and extending downwardly therefrom, and through an opening 18 in shelf 17 of the side frame. The lower faces of these trunnions are beveled, as shown at 23a and 23b.

Cooperating with these beveled faces are wedges or friction shoes 24, there being two of these shoes for each trunnion. These shoes rest upon the upper ends of the lower springs 19. The angular contact between the bolster trunnions and shoes, and the upward reaction of the springs 19 forces each shoe outwardly against a hardened wear liner 25 which seats in the opening 18 in the shelf portion 17 of the side frame. Each of these wear liners 25 has an uninterrupted, preferably cylindrical, inner face for frictional contact with the outer face of the corresponding friction shoe 24. Extending outwardly from the upper end of each wear liner is a shoulder 26 which fits into a correspondingly recessed part 27 of the shelf 17 and thus prevents movement of the liner downwardly.

It will be seen that each side frame assembly consists of two friction systems, spaced apart from each other and arranged lengthwise of the side frame. Between these two friction systems and above them is the central one of the three upper springs 20.

In order to prevent any upward movement of the four wear liners and to hold them tightly in place, I provide a special hold-down clamp 28, as shown in detail in Figure 4 and assembled in Figures 1, 2 and 3. This clamp is roughly rectangular in shape with each of its four corners 28a overlying a part of one of the wear liners 25 and resting thereon. The central part of the clamp is depressed at 28b and forms the seat for the lower end of the center one of the springs 20. The thickness of the body of the clamp is so adjusted with respect to the depth of the recesses 27 in shelf 17 and the thickness of the support shoulders 26 of the wear liners 25, that the clamp is supported entirely upon the four wear liners. The entire reaction of the center one of the springs 20 is therefore effective in holding the four wear liners securely in place. The top surface of the spring seat in part 28b of the clamp is so located with respect to the top surface of the wear liners upon which the clamp rests, that the top surface of part 28b is level with the surface of the spring seating portion 17 of the side frame. Thus all three springs 20 are compressed the same amount by the bolster.

The ends of clamp 28 are relieved at 28c to clear the inner and outer bolster springs 20 and the sides of the clamp are recessed or notched at 28d to clear the friction shoes 24.

It will thus be seen that I have provided a truck spring suspension consisting of five springs, all acting in parallel to support the bolster. Three

of these springs support the bolster directly, while the other two support the bolster through friction generating means.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a railway car truck, a side frame and a bolster, spring seats on said side frame and bolster, said side frame having a depressed portion between said side frame spring seats, friction members in said depressed portion, spring-actuated friction shoes engaging said members, an element seated in said depressed portion between said friction members having projections overlying said friction members to limit upward movement thereof upon upward movement of said friction shoes, a spring seat portion on said element and a spring seat portion on said bolster directly above said element, the distance between said spring seat portions being substantially the same as the distance between said side frame and bolster spring seats.

2. In a railway car truck, a side frame and a bolster, said side frame having a shelf with a pair of openings therein and a depressed portion, friction members supported by said shelf, a spring seat element in said depressed portion between said openings having portions thereof engaging upper surfaces on said friction members, and a spring resting on said element and supporting said bolster adapted with said element to restrain upward movement of said friction members.

3. In a railway car truck, a side frame and a bolster, said side frame having a shelf with a depressed central portion, friction members carried by said side frame having portions thereof received in said depressed central portion, spring means on said shelf on each side of said depressed central portion a spring seat element in said de-

20 pressed central portion having a spring engaging surface on the same level as the upper surface of said shelf and having means thereon engaging upper surfaces on said friction members, and a spring resting on said surface and supporting said bolster adapted with said element to restrain upward movement of said friction members.

4. In a railway car truck, a side frame and a bolster, said side frame having a shelf with a depressed central portion, friction members carried by said side frame having portions thereof received in said depressed central portion, spring means on said shelf on each side of said depressed central portion, a spring seat element in said depressed central portion having a spring seating surface on substantially the same level as the spring engaging surface of said shelf, said element having means thereon adapted to engage said friction members to restrain upward movement thereof.

5. A side frame for a railway car truck, said side frame having a shelf with a depressed central portion, spring seats on each side of said central portion, friction members supported by said shelf having portions received in said depressed central portion, and a spring seat member in said central portion having lugs overlying said friction members and having a spring seating portion at substantially the same level as said spring seats.

6. A spring seat member for railway car truck comprising a seating portion adapted to receive a bolster supporting spring, an upstanding flange on said member on each side of said seating portion adapted to position said spring and a plurality of lugs extending laterally from said seating portion, the under surfaces of said lugs being substantially in the same horizontal plane as said seating portion when said member is assembled in a car truck, said surfaces each being adapted to engage a friction member of a friction system to limit upward movement of the friction members.
